SIFTER

Thomas G. Cecka, Buffalo, N. Y., assignor to
International Milling Company, Buffalo, N. Y.

Application May 24, 1938, Serial No. 209,694

11 Claims. (Cl. 209—332)

This invention relates to improvements in sifters.

It has heretofore been customary to construct sifters including a plurality of sieves arranged in a vertical tier, and suspending this tier of sieves by means of reeds from an overhead support, and then driving the sifter by means of eccentric weights mounted on the sifter to produce circular motion of the same and it has been common practice to provide these weights or eccentrics in pairs one arranged above and the other below the tier of sieves. These sifters were generally operated at a speed of about 175 to 190 revolutions per minute and the weights were disposed so as to produce motion of the sieves in circles of about four inches diameter.

Since sifters of greatly increased capacity and operating at speeds of about 300 revolutions per minute were introduced by me, attempts have been made to apply these higher speeds to sifters suspended from overhead supports and also to operate such sifters by applying rotary motion thereto at one end only of the sifter housing. It was found, however, that such attempts resulted in an excessive amount of circular motion of the end of the sifter opposite to that to which the circular motion was applied and that such excessive motion not only interfered with the proper and efficient sifting of the material but also was destructive of the sifters.

One of the objects of this invention is to provide a new and improved method of sifting by means of which greatly increased sifting capacity and speed is attained.

It is also an object of this invention to provide a sifter of the suspended type capable of operating at speeds of about 300 revolutions per minute, and in which excess movement of the portion of the sifter remote from that to which circular motion is applied, is prevented. It is also an object of this invention to provide a sifter in which the reeds used for suspending the sifter are also employed for preventing excessive movement of any part of the sifter. A further object of this invention is to provide a sifter in which the sifter housing is suspended from reeds, and in which the reeds are secured both to the upper and to the lower portion of the sifter housing. Another object is to provide a sifter having circular motion imparted to the lower portion of the housing and having the housing suspended from an overhead support by means of flexible reeds secured to the upper and lower portions of the housing, so that the weight of the housing applies tension to the reeds which in turn enables the

reeds to better restrain the upper part of the housing against excessive circular motion.

Another object of this invention is to provide a sifter housing of novel construction, which comprises a plurality of superimposed sieve frames arranged so that the outer walls of the sieve frames form the housing of the sifter. It is also an object to provide means of improved construction for confining the sieve frames in correct relation to each other to form a sifter housing.

A further object of this invention is to provide means of improved construction for varying the throw or the diameter of the circular motion imparted to the sifter housing.

Other objects of this invention will appear from the following description and claims.

In the accompanying drawings:

Fig. 1 is a side elevation of a sifter embodying this invention.

Fig. 2 is a sectional plan view thereof, on line 2—2, Fig. 1.

Fig. 3 is a fragmentary sectional elevation thereof, on line 3—3, Fig. 2, on an enlarged scale.

Fig. 4 is a sectional view, on line 4—4, Fig. 1, showing the top plan view, partly in section, of the sifter housing.

Figs. 5 and 6 are fragmentary transverse sectional elevations of the sifter housing respectively on lines 5—5 and 6—6, Fig. 4.

Fig. 7 is an elevation, partly in section, of a sifter of modified construction.

Fig. 8 is a fragmentary elevation, partly in section, of an upper corner portion of the sifter housing shown in Fig. 7.

The word "sifter" as herein employed is intended to indicate an apparatus for sifting, screening, or bolting flour, feed or other finely divided or granular materials for separating the same according to particle sizes. The sifter shown in the accompanying drawings illustrates by way of example one embodiment of my invention, and it is not intended to limit this invention to the particular construction or form of the sifter shown in the drawings, since it will be obvious that my invention is applicable to sifters of other constructions. The sifter may include one or more sieves or screens of the desired mesh.

The particular sifter shown in Figs. 1 to 6 includes a bottom 10, which is provided with a plurality of discharge ducts 11 for the material which has been sifted, and a plurality of sifter frames 12 are arranged in a vertical tier above the bottom 10. Above the uppermost of these

sieve frames is a top member 14 provided with suitable inlet ducts 15. The ducts 11 and 16 may be in the form of flexible tubes such as commonly used in connection with sifters. In the particular construction illustrated in Figs. 1 to 6, the outer walls of the sieve frames or boxes 12 constitute the walls of the sifter housing, and the upper and lower edges of the walls of the sieve frames may be provided with the usual dust-tight gaskets (not shown). The walls of the sieve frames may be held in correct relation to each other in any suitable or desired manner, and in order to avoid the use of any outer wall or casting for confining the sieve frames in correct relation to each other, I preferably provide each 10 sieve frame at the corners thereof with angle-shaped members or corner pieces 17 which extend beyond the upper or lower edges of the sieve frame so as to overlap portions of the corners of an adjacent sieve frame. In the construction shown, the corner pieces 17 are secured to the sieve frames 12 in such a manner as to extend slightly below the lower edge portions of each sieve frame, and consequently, to engage 20 the adjacent upper corner portions of the next lower sieve frame. The lowest sieve frame 12 may be held in correct relation to the bottom 10 in some other manner, for example, by means of an upwardly extending outer flange 18, so that the lower sieve frame has no corner pieces 11. 30 The top member 14 of the sifter housing is also provided with corner pieces or brackets 20 of somewhat larger size which overlap the corners of the top sieve frame 12.

In addition to being held in correct vertical alignment with relation to each other, means are preferably also provided for securing the sieve frames and the top and bottom of the sifter housing against vertical displacement relatively to each other. Any suitable means may be provided for this purpose, and in the construction shown, an upright bolt or tie rod 22 is provided at each corner of the sieve housing, which extends through holes in the sieve frames 12 and in the top and bottom members 14 and 10 of the sifter housing. These tie rods may be reasonably held in place by means of nuts 24 having threaded engagement with the lower ends of the tie rods.

As a result of the construction described, any or all of the sieve frames can be easily removed from the apparatus by releasing and removing the tie rods. Consequently, the sieve frames can be easily removed for cleaning, or the sieve frames can be replaced by others having sieves of different mesh. Also sieve frames with broken sieves can be quickly removed and replaced. It will also be obvious that the number of sieve frames may be varied according to the needs of the user of the machine by merely providing tie rods of the required lengths.

Any suitable or desired means may be employed for imparting circular motion to a sifter housing, and if desired, rotary eccentric members or 65 weights may be rotatably mounted on one end of the sifter housing, for example, on the lower end, as has heretofore been frequently done, or if desired, such circular motion may be applied to the sifter housing by means of a crank or 70 eccentric rotatably journalled on a suitable base arranged below the sifter housing. The latter construction is illustrated by way of example in the accompanying drawings, in which 25 represents a base which may be secured to the floor 75 below the sifter housing, and which has a cen-

tral upwardly extending hub portion 21 in which an upright rod or shaft 28 is journalled in any suitable or desired manner. This shaft is rigidly connected with a crank pin or eccentric 29 which is journalled in a self-aligning bearing 30 suitably secured to the bottom member 10 of the sifter housing. The upright shaft 28 may be rotated in any suitable or desired manner, for example, by means of a pulley 31 and belt 32 connected with any suitable driving means (not shown). Because of the eccentricity of the crank 29 and the forces acting thereon, the pulley 31 is preferably provided with a suitable counterweight 33, as has heretofore been common practice, to reduce vibration of the shifter.

From the foregoing description, it will be obvious that when the shaft 28 and crank 29 are rotated, a circular motion will be imparted to the bottom of the conveyor housing. If the speed of this circular motion is materially increased over the speed of about 175 revolutions per minute, which was heretofore commonly employed, the manner of supporting the shifter housing heretofore employed is inadequate in that the upper part of the sifter housing would tend to swing about a much greater radius than the radius about which circular motion is imparted to the bottom of the sifter. Consequently, in order to form a suitable support for the sifter housing, I provide flexible supporting means or reeds which are secured to the lower part of the housing to suspend the housing from an overhead support and I also provide means for resiliently opposing such excessive movement of the upper part of the sifter housing. I have also found that this can be very effectively accomplished by connecting these flexible means or reeds with the upper portion of the sifter housing so that the suspending members limit the extent of movement of that end of the sifter housing opposite to that to which rotary motion is imparted. The suspending means may, for example, be in the form of a plurality of reeds 35 such as have heretofore been frequently employed in connection with sifters of this general type. The upper ends of these reeds may be secured to any suitable holding members 36 which are in turn secured to a ceiling or other overhead support. The reeds are connected to the sifter housing by suitable clamping or securing members which may be in the form of corner pieces or brackets 37 secured to the bottom member 10 of the sifter housing and extending outwardly therefrom. These clamping members may be similar to those heretofore used in connection with sifters suspended from overhead supports, and are not herein shown in detail. Similar clamping members 38, which may be a part of and extend outwardly from the corner pieces 20 of the upper member 14 of the sifter housing, may be employed for securing the upper part of the housing to the reeds 35, but any suitable means for connecting this part of the housing to the reeds intermediate of their ends may be employed. The reeds support the weight of the sifter housing and this weight, consequently, places the reeds under tension. This tension together with the inherent rigidity of the normally straight reeds, yieldingly opposes the tendency of the upper part of the housing to move in a circle of greater diameter than the lower part of the housing. This restriction of the movement of the upper part of the housing produces a movement of the screens which results in a greatly increased capacity of each screen. It has been found that

sifters constructed as herein described have, when used on some materials, materially greater capacity than sifters having their housings mounted on reeds extending upwardly from a base and operated at a speed from about 290 to 310 revolutions per minute with a throw to make a circle from about one and one-half to two inches, depending on the nature of the stock to be shifted. While I do not know why sifters such as herein described have such greatly increased capacity, yet it is probable that the particular connection of the sifter housing with the rods at the top and bottom of the housing results in a peculiar flexing of these rods so that they impart a movement to the sifter housing and to the sieves a motion which produces the type of agitation of the material on the sieves which results in a rapid passage of the fine material through the sieves.

From the foregoing, it will be clear that my improved method of sifting material comprises depositing material to be sifted on the upper surface of the sieves in the housing, applying to one end of the housing a motion in a circular direction, preferably at a radius not more than about one inch and at a speed of approximately 300 revolutions per minute and yieldingly supporting the sifter housing while motion is applied thereto in this manner, for example, by means of flexible reeds which are secured to the one end of the housing, for example, the lower end, and yieldingly opposing movement of the other end of the housing so as to prevent movement of the same in a circular path of materially more than two inches diameter. This part of the process can be most readily carried out by means of a connection between said other end of the housing with the flexible reeds or supporting means so that they confine and restrict the motion of the upper portion of the housing. My improved method also includes the application of the weight of the housing and the parts connected therewith to the reeds so that the tension thus placed on the reeds will assist in confining the movement of the upper portion of the housing. As has been stated, this method of sifting results in a very high capacity of the sifter and in a rapid passing of the material through and over the sieves.

In sifters of this type, it may be desirable at times to provide the sifter with means for varying the throw of the lower part of the sifter, since with different materials, different movements or throws are required to produce the maximum capacity of the sifter. This variation in throw may, of course, be obtained by providing a different crank pin, or if desired, an adjustable crank pin may be provided. An arrangement of this kind is shown in Figs. 2 and 3, in which the upright rod or shaft 28 and the crank pin 29 are formed in two separate parts, and these two parts are connected in such a way as to permit one to be adjusted relatively to the other. For this purpose, I provide at the upper end of the upright shaft 28 a part 40 of enlarged diameter. This enlarged part has a transverse slot 41 formed therein. The crank pin 29 is formed with a base 42 in the shape of a rectangular bar adapted to fit into the slot 41 and to extend beyond the ends of the slot. The pulley 31 preferably has an elongated hub portion 45 provided with a longitudinally extending slot 46, the middle portion of which is of substantially cylindrical form as indicated at 47 to receive the enlarged upper end 40 of the upright shaft 28. This slot 46 receives the ends of the base 42 of the crank pin 29 and

also the means for adjusting this base lengthwise of the slot 46. Any suitable means may be provided for adjusting the base 42 lengthwise of the slot and for securing the base in its adjusted position during the operation of the apparatus. In the particular construction shown, I have provided a pair of wedges 48 and 49 arranged at opposite ends of the slot 46 and these wedges have inclined faces which are adapted to engage with correspondingly inclined faces of the ends of the base member 42. Consequently, it will be obvious that if one of the wedge members is moved upwardly while the other is moved downwardly, the base 42 will be moved lengthwise of the slots 46 and 41. Consequently, by adjusting the wedges in this manner, the crank pin 29 may be moved toward and from the vertical axis of the upright shaft 28 to the desired extent, thus changing the diameter of the circle of movement of the crank pin.

The wedge blocks 48 and 49 may be locked in their adjusted positions in any suitable or desired manner, and for this purpose, I provide a pair of adjusting screws or bolts 51 and 52 which extend through holes in the hub portion of the pulley 31 and which have threaded portions engaging in correspondingly threaded holes in the wedge blocks 48 and 49. Consequently, by means of the bolts 51 and 52, the wedge blocks 48 and 49 may be adjusted as desired and also rigidly secured in their adjusted positions by tightening both adjusting screws. This construction also avoids the necessity of providing a key for connecting the shaft 28 with the pulley 31, since the base 42 of the crank pin engaging the slotted portion of the upright shaft 28 and in the slotted portion 46 of the hub serves to form a driving connection between the pulley 31 and the upright shaft 28. Any other means for adjusting the throw of one end of the sifter housing may be employed in place of that shown, or if desired, a drive shaft as heretofore employed, having a crank pin formed integral therewith may be provided to produce a fixed throw for the lower end of the sifter housing. It will also be obvious that while I have shown the sifter housing actuated by a positive drive mounted on a fixed base, yet an eccentric weight may be provided on the lower end of the housing for producing the desired circular movement of the lower end of the housing, such as has heretofore been frequently used for imparting motion to sifter housings. When such eccentric weights are employed, it is necessary, however, to provide weights of such size and so positioned relatively to the sifter housing that the lower end of the sifter housing will move approximately in a circle of from one and one-half to two inches diameter, and this throw is also desirable when the circular motion is imparted to the lower end of the sifter by means of a crank or eccentric as shown in the accompanying drawings. This throw of the lower end of the sifter housing is essential to the high capacity of the sifter when driven at approximately 300 revolutions per minute.

In Figs. 4 to 6, I have shown by way of example, some sieves which may be employed in connection with my improved sifter housing. These sieves may be similar to those shown in my copending application Ser. No. 87,198 filed June 25, 1936, or may be of any other suitable or desired construction. Briefly stated, each sieve has an inner sieve supporting frame 55 arranged within the main or outer sieve frame 52. To the upper edges of the inner sieve supporting frame, 75

a screen or sieve 56 of the desired screening material may be secured. Preferably, the inner sieve supporting frame 55 includes a partition or dividing wall 57 extending completely across the interior of each frame 12 and separating the sieve into two separate parts, and when the sieve frames 12 are arranged one above the other, these upright partition walls 57, in cooperation with similar walls 58 of the upper frame member 14 completely divide the interior of the sifter housing into two halves, each of which may be supplied with different materials through the flexible tubes 15, or if desired, the same material may be discharged through both of the tubes 15. Below each sieve 55, there is preferably provided a coarse wire screen 59 upon which the usual cleaning brushes (not shown) may be supported which move along the undersurface of the screens 56 to prevent plugging of the same. Below each coarse mesh screen 59, there is provided an imperforate deflector plate or tray 60 upon which material which has passed through the sieve 56 drops.

Each of the inner sieve frames is so arranged within the outer sieve frame 12 as to be spaced on three sides thereof from the corresponding three sides of the outer sieve frame, the fourth side of the inner frame being secured directly to the outer frame 12. The inner sieve frames are also arranged in staggered relation to each other, as shown in Fig. 5, so that material discharged from the upper surface of the screen 56 of one inner sieve frame drops through a space 62 between this inner sieve frame, and the outer sieve frame 12 upon the sieve of the next lower frame. The material to be sifted is, consequently, cascaded from one sieve to the next and some of this material may, consequently, pass over all of the sieves of the sifter housing, but if desired, the sieve frames may be readily constructed and arranged so that each sieve or any group of sieves operates independently of the other sieves.

At opposite sides of the machine, the inner sieve frames are spaced from the outer sieve frames to form a series of vertically aligned spaces 63 which form upright passages 64 into which the material which has passed through the sieves 56 is discharged. This is preferably accomplished by providing each inner sieve frame at opposite sides thereof with slots 64 arranged between the deflector plate or tray 60 and the coarse wire screen 59, see Fig. 6, so that the material which has passed through the sieves is discharged from each sieve frame downwardly through the upright passages 65 and is carried from the sifter through one pair of flexible tubes or ducts 11, as shown in Fig. 6, while the coarse material which has not passed through the sieves is discharged through the other sets of sleeves or ducts 11, as shown in Fig. 5. Sieves of any other suitable or desired form may, of course, be employed in place of those described. Figs. 4, 5 and 6 represents carrier flights in the form of short plates or vanes arranged above each sieve at one side thereof to deflect the material across the sieve toward the discharge end thereof during the motion of the sieve housing. Preferably, these carrier flights are secured to each sieve frame below the tray 60 thereof so that, when the sieve frames are assembled, the carrier flights of one sieve frame will be above the sieve or screen 56 of the next lower sieve frame.

In Figs. 7 and 8, I have shown my invention applied to a sifter having a different form of housing, including an outer shell or box 70 within

which the various sieve frames 69 are arranged. The side walls of the box 70 are rigidly secured to the bottom plate 71 of the sifter housing and suitable braces 72 may be provided for reinforcing the upper portion of the sieve box or outer housing. In this case, the sieve box or outer housing is also provided at opposite ends thereof with suitable brackets 74 and 75 extending outwardly, preferably from the corners thereof and to which the upright reeds 76 may be secured. In this sifter, the sieve frames 69 may be clamped together by vertical pressure in any suitable manner. For example, an upper plate 77 may be provided at intervals with suitable brackets 78 secured thereto and having portions thereof extending outwardly beyond the outer shell or housing 70. Preferably, these portions of the brackets extend above the brackets 78 and clamping bolts 79 suitably secured to the corner brackets 75, as clearly shown in Fig. 8, and may pass through holes in the brackets 78 of the top plate 77. Each bolt 79 has a clamping nut 80 engaging a bracket 78 to apply pressure to urge the top plate 77 downwardly against the sieve frames 69, and thus clamp these sieve frames against the bottom 71 of the outer housing or box of the sifter.

While the sifter-housing construction disclosed in Figs. 7 and 8 operates very successfully in connection with my improved sifter and is preferable to the structure shown in Figs. 1 to 6 from the standpoint of absolutely preventing escape of dust and protecting the sieve frames against damage, yet for many purposes, I prefer to employ the sifter housing construction shown in Figs. 1 to 6, in which the outer housing or sifter box is entirely eliminated. The construction shown in Figs. 1 to 6, therefore, not only reduces the weight of the sifter housing, but also renders the individual sifter frames 12 much more readily accessible and eliminates the housing of insects or other vermin between the outer housing and the housing formed by the outer walls of the sieve frames 12. By nesting these sieves one upon another, as shown in Fig. 6, and then clamping them tightly together, it is very easy to dismantle the complete machine so that the sieves can be easily brushed or otherwise thoroughly cleaned.

In addition to the advantages already stated, the sifter herein described has the further advantage that the same is adaptable for use in connection with a large variation in the number of sifter frames which may be employed. It is possible to operate the sifter with only a single sieve or screen, and if desired, as many as 17 or more such sieves can be employed. Such a large number of sieves cannot be used with sifters supported from a base by means of flexible reeds as described in my aforesaid copending application, since the sifter housing then becomes too topheavy. In sifters in which the sieve frames are supported from the base, if too many sifter frames are supported one above the other, the column becomes so high that it is impossible to control the motion of the upper sieves. With the construction herein described, however, it has been found that the movement of the upper end of the sifter housing is not much different when a large number of sieve frames is employed, than it is when a smaller number is used. This is undoubtedly due to the restraining influence of the reeds which engage both the upper and lower end of the housing, and since this restraining influence is due to some extent to the weight of the sifter, which tends to draw the reeds into straight

- line positions, it will be obvious that when a large number of sifters is employed, the correspondingly increased weight of the sieves housing will result in the reeds exerting greater force to restrain the upper sifter members against excessive movement, thus compensating for the greater tendency of the upper end of the sifter housing to move in a larger circle when a large number of sieve frames is used.
- 5 10 I claim as my invention:
1. A sifter having a sieve housing containing a sieve upon which material to be sifted is deposited, and which is located intermediate of the upper and lower ends of said housing, means for imparting rotary motion to one of said ends only of said sieve housing, and reeds for suspending said housing from an overhead holding means, said reeds engaging said housing near the upper and lower ends thereof and having the weight of 15 20 said housing applied to the reeds from the lower end of said housing.
2. A sifter having a sieve housing containing a sieve upon which material to be sifted is deposited, and which is located intermediate of the upper and lower ends of said housing, means for imparting rotary motion to the lower end only of said sieve housing, flexible supporting means each connected at its upper end to an overhead holding means and at its lower end to the lower portion 25 30 of said housing, and means for yieldingly opposing movement of the upper portion of said housing to restrict the same to movement not materially greater than the motion imparted to the lower end of said housing.
3. A method of sifting material, which comprises disposing a sieve between the upper and lower ends of a housing in a position to support material to be sifted on its upper surface, depositing material to be sifted on said upper surface, applying to the lower end of said housing a motion in a circular path, yieldingly supporting the lower end of said housing, and yieldingly confining the movement of the upper portion of said housing to a circular path not substantially greater than said first mentioned circular path.
4. A method of sifting material, which comprises disposing a sieve between the upper and lower ends of a housing in a position to support material to be sifted on its upper surface, depositing material to be sifted on said upper surface, applying to the lower end of said housing a motion in a circular path, yieldingly suspending the lower end of said housing, and restricting the movement of the upper end of said housing by connecting the same with the means for suspending the lower part of said housing.
5. A support for a sifter housing, which contains a plurality of sieves arranged one above another and which has circular movement applied thereto at one end only, said support including a plurality of reeds suspended at their upper ends and connected with both the upper and lower portions of said housing, the connection of said reeds with the lower portion of said housing placing the weight of said housing on said reeds.
6. A support for a sifter housing, which contains a plurality of sieves arranged one above another and which has circular movement applied to the lower end only thereof, said support including a plurality of reeds secured at their upper ends to an overhead holding means and connected at their lower ends with the lower end of said housing to support the weight thereof, the upper end of said housing being connected with said reeds intermediate of the ends thereof, whereby the reeds resiliently hold the upper end of said housing against movement in a circle of excessive diameter.
7. A support for a sifter housing, which contains a plurality of sieves arranged one above another and which has circular movement applied to the lower end only thereof, said support including a plurality of reeds secured at their upper ends to an overhead holding means and secured at their lower ends to the lower portion of said housing to carry the weight of said housing, and means for connecting the upper portion of said housing with said reeds, whereby the tension on said reeds due to the weight of said housing resists excessive movement of said upper portion of said housing.
8. A sifter including a housing, reeds for suspending said housing from an overhead holding means, said reeds being connected with the upper and lower portions of said housing and receiving the weight of said housing through the connection with the lower portion thereof, and means for applying circular motion to the lower portion of said housing.
9. A sifter including a housing, reeds for suspending said housing from an overhead holding means, said reeds being connected with the upper and lower portions of said housing and receiving the weight of said housing through the connection with the lower portion thereof, a base mounted on a fixed base below said housing and having a crank rotatable about a substantially upright axis, and means for connecting the lower end of said housing with said crank for imparting circular motion to the lower end of said housing.
10. A sifter including a housing, reeds for suspending said housing from an overhead holding means, said reeds being connected with the upper and lower portions of said housing and receiving the weight of said housing through the connection with the lower portion thereof, a base rigidly mounted below said housing, an upright shaft journaled in said base and having a crank, a self-aligning bearing connecting the lower part of said housing with said crank, and means for rotating said shaft.
11. A sifter including a plurality of sieves stacked one upon another and having outer walls forming a sieve housing, interengaging means on said sieves which hold each sieve against shifting laterally relatively to an adjacent sieve to hold said sieves against displacement out of their stacked positions and permitting said sieve frames to be separated vertically, a bottom member upon which the stack of sieves rests, a top member resting upon the upper sieve and held against lateral movement thereto and through which material to be sifted passes to said sieves, a plurality of reeds suspended from their upper ends, means for securing the lower portions of said reeds to said bottom member, means on said top member engaging said reeds for restricting lateral movement of said top member and said stack of sieves, and means for imparting motion in a closed loop path to said bottom member.

THOMAS G. CECKA. 70
